UNITED STATES PATENT OFFICE.

DAVID C. KLAUSMEYER, OF HYDE PARK, CINCINNATI, OHIO, ASSIGNOR TO CINCINNATI BICKFORD TOOL COMPANY, OF OAKLEY, CINCINNATI, OHIO, A CORPORATION OF OHIO.

REVERSING MECHANISM HAVING STATIONARY SLEEVE.

Application filed April 13, 1921. Serial No. 461,144.

To all whom it may concern:

Be it known that I, DAVID C. KLAUSMEYER, a citizen of the United States, and residing at 3638 Burch Ave., Hyde Park, Cincinnati, 5 in the county of Hamilton and State of Ohio, have invented a new and Improved Reversing Mechanism Having Stationary Sleeve, of which the following specification is a full disclosure.

10 This invention appertains to motion-reversers and it deals more especially with the type employing conversely-running bevel-gears combined with clutches and controlling means therefor.

15 Such motion-reversers, present many mechanical problems on account of the necessity of simultaneously attaining strength, precision, durability, reliability, smoothness, simplicity and cheapness; all by means of an 20 organization condensed within a very restricted compass. One prominent defect of such arrangements as have previously most completely reconciled these more or less conflicting desideratum resides in the mounting 25 of two conversely-rotating gears on either a shaft or a sleeve or other member which itself is subject to an absolute rotation equal to the absolute rate of each gear but in alternate directions thereto, with the effect that the rate between it and each of the gears in 30 turn is twice the absolute rate of the gear itself. As a result, each gear in reality runs twice as fast on its bearing as it would if said bearing was fixed.

35 It has for long been recognized that this condition was provocative of undue wear but no cure, compatible with other structural necessities, has heretofore been developed.

40 By virtue of the structure herein proposed, this defect has been eliminated without, however, necessitating the sacrifice of certain other very desirable structural characteristics.

45 The high relative motions previously noted, together with the degree of looseness occasioned thereby and incidental thereto, likewise obtained between the movable parts of the clutch and, considering the nature of the bearings resorted to, had the effect of 50 prohibiting the use of certain very desirable types of clutch; notably, so-called "disk" clutches, and also "cone" clutches. This prohibition followed from a tendency to accentuate the eccentricity which much needs

exist to some extent initially, and to a great 55 extent in time, due to the impossibility of attaining absolute precision in any mechanism. This invention proposes a construction admitting of the use of laterally-operating clutches which, for purposes of definition, are herein termed "disk" clutches; this term being employed to contemplate the various species of clutches characterized by having two or more flat or conical friction surfaces, such for example, as either multiple 60 or single disk clutches, or cone clutches.

65 Furthermore, in motion-reversers of this description, a plurality of parts are of necessity arranged in co-axial relation and the smoothness of action, durability, and general 70 efficiency depends very largely upon the initial precision and maintenance of the co-axial relation. An objective of this invention is to provide a structure whereby this co-axial relation, from the manufacturing 75 standpoint, may accurately be obtained initially and maintained subsequently without entailing undue cost, or undue manufacturing difficulties. Moreover, it is not only necessary that the gears shall initially be arranged to intermesh accurately with respect 80 to their pitch-lines, but also provision must be made, whereby they may be adjusted in this respect to compensate their wear. This adjustment must also be compatible with the 85 preservation of a correct operative relation with the clutches associated with the gears. This desideratum is likewise provided for in an effective manner by the structural arrangement herein proposed; it being achieved 90 without interfering with the attainment of compactness.

95 Other objects and advantages will be in part indicated in the following description and in part rendered apparent therefrom in connection with the annexed drawings.

To enable others skilled in the art to so fully apprehend the underlying features hereof that they may embody the same in the various ways contemplated by this invention, drawings depicting a preferred typical construction have been annexed as a part of this disclosure, and in such drawings like characters of reference denote corresponding parts throughout all the views, of which:— 100 105

Fig. 1 is a longitudinal section showing the general assembly of the element of this device. Fig. 2 is a transverse section taken

along line 2—2 of Fig. 1 showing the arrangement of the lever for operating the clutches. Fig. 3 is a section through line 3—3 of Fig. 1. Fig. 4 is a fragmentary 5 longitudinal section showing a slight modification of the mounting of the clutches on the stationary sleeve. Fig. 5 is a section through line 5—5 of Fig. 4 showing the manner of connecting the clutches with the 10 shaft in this modification. Fig. 6 is a longitudinal section showing a still further modification in which the clutches are mounted directly on the shaft.

Continuing now by way of an analysis of 15 the herein illustrated examples of this invention, 1 indicates a frame for supporting and positioning the major elements of the device. While this frame may be open, it will be formed in the nature of a closed 20 casing in the preferred aspect of this invention, so that the various bearings may be shielded against grit and may be run in a bath of oil or grease. This frame is characteristically provided with means for 25 providing stationary journals for the mounting of two conversely-rotating bevel-gears. A convenient way of achieving that end is illustrated in Figs. 1 and 2, wherein 2 indicates a bracket internally projecting from 30 a side-wall of the casing; it being firmly affixed thereto by a screw 3. This bracket provides an elongated bearing-element 3 in the nature of a stationary sleeve; the ends 35 4 and 5 of which constitute stationary journals or bearing members on which the gears are rotatably mounted.

The shape of the bracket is, of course, immaterial so long as it admits of being arranged in the intermediate position shown 40 and it is, of course, immaterial whether the journals 4 or 5 are integral with said bracket 2 or are otherwise rigidly attached to it.

The casing 1 is provided with a bearing 6 located intermediate the ends of the stationary sleeve 3 and this receives a shaft 7 having affixed to its inner end a bevel-gear 8 which, accordingly, faces the stationary sleeve 3 substantially midway its ends. Mounted on the stationary journals 4 and 50 5, are two bevel-gears 9 and 10 which are in mesh with the bevel-gear 8, as shown by Fig. 1. As will be understood, the effect of this intermesh is to urge the gears 9 and 10 away from the axis 2—2 of the shaft 7 and, in order to limit this movement, suitable thrust-bearings are provided adjacent of outer faces of the gears 9 and 10. These gears are rotatably, as well as translatable, mounted on the journals 4 and 5 (as for example through the agency of the brass bushing 11) so as freely to admit of movement against the said thrust bearing. In the course of time, sufficient wear will take place to impair the original precision of the 55 intermesh and, therefore, provision is made

for adjusting the gears toward the axis line 2—2. To that end, a collar 12 is screw threaded to the end of the stationary sleeve 3 so that it may be adjusted towards the axis line 2—2; a thrust bearing 13 (preferably of the ball type) being interposed for the purpose of decreasing friction and wear. Inasmuch as both the gears 9 and 10 are journaled on a single stationary element, they admit of being held very closely in 75 an accurate co-axial relation; there being no intervening loose element to impair the precision of the mount. In previous motion reversers, the opposed bevel gears were habitually mounted on a rotary member; this 80 member being in turn suitably connected to some other element of the transmission train. Through the agency of appropriate clutches, either gear could be connected with said rotary member so that the two would 85 rotate together as a unit; leaving the other gear free to rotate independently of the member on which it was mounted but in a direction opposite thereto. The relative motion between the two was accordingly twice 90 as fast as if the member had had no rotation itself. This condition tended towards premature wear and occasioned earlier replacements and troubles; notwithstanding extreme care in lubrication. The instant 95 construction avoids this difficulty in a manner entirely compatible with compactness and other desideratum.

The gear 9 is of small diameter and its bore is comparatively small so that, while 100 permitting the gear 8 to be set close to the central axis of the spindle, it will nevertheless run smoothly. While such gear 9 may have its outer portion configurated in any manner appropriate to the type of clutch 105 used, it will be noted that the example illustrated presents a very desirable characteristic; to wit, it merely has a simple disk-like flange 14 of small diameter formed on its end; thereby avoiding the complicated 110 cup-like formations heretofore demanded to meet the necessities of clutches of the expanding ring type previously required for various structural reasons in mechanisms of this general nature. It is, of course, much 115 cheaper to manufacture gears of the simple form shown in the herein illustrated preferred embodiment of this invention, since the disk-flange 14 may not only be made integral with the gear itself but may be 120 formed from the original blank without requiring the removal of any great amounts of stock which, of course, is of high-grade 125 expensive steel.

This flange 14 may be regarded as the 125 male member of the clutch or, as a matter of nomenclature, the clutch may be referred to as consisting of the various movable and adjustable elements comprising the separate unit now to be described. This device com- 130

prises a body proper 15 in the nature of a cup-like member having a hub 16 in the form of a sleeve and an annular flange 17 having a rim 18 projecting towards the gear so as to provide a recess, or chamber 19 for the accommodation of the thrust bearing 18, the adjustable ring 12, or other parts.

The arrangement proposed by this invention admits of various mountings of the clutch-member 15 as will be perceived by comparing Figs. 1, 4 and 6, thus, it may be carried directly by a shaft, or by a rotatory sleeve, or by the stationary sleeve on which the gear 9 is directly journaled.

The general object of motion reversers of the sort in view, is to enable motion to be transmitted from a shaft 7 to another shaft 20 arranged at an angle thereto; usually in the same axial plane therewith and usually also at right-angles thereto, but not necessarily so. The shaft 20, however, must admit of being translated in an axial direction relative to the shaft 7 without any break in the connection but otherwise accurately preserving the spatial relations between the two. The shaft 20 is, accordingly so journaled (either directly or indirectly) with respect to the frame that the aforesaid relation will be preserved, and also so connected (either directly or indirectly) with the clutch as to preserve the driving relation in all of its positions. The former may be achieved directly by providing the stationary sleeve or journals with a bore in which the shaft rotates, as shown by Fig. 6; or it may be achieved indirectly by resorting to an intervening sleeve arranged, on the one hand, to serve as a bearing for the shaft and being, on the other hand, itself journaled within the bore of the stationary sleeve or in the side walls of the casing. Thus, as shown by Fig. 1, an elongated tubular sleeve 21 is splined to the shaft 20 by means of the key 22 and is also (as by means of bushings 23) journaled within the bore of the stationary sleeve 21 which, in effect, is a fixture or part of the casing. These journals 23 are preferably spaced apart and located near the ends of the fixed sleeve, as shown, so as to ensure accuracy in alignment and, in case a closed casing be used, the rotary sleeve preferably will extend into openings 24 in the side-walls 25 thereof to make provision for dust-guards 26 in the nature of packing adapted to prevent undue leakage of the lubricant. The end-portions 27 of the rotary sleeve may also be journaled in said openings if desired to ensure the alignment and, to restrict the end-play, the rotary sleeve may be provided with an ample shoulder 28, as shown by Fig. 4, bearing directly against the side-wall of the casing, or it may have a shoulder 29 and an intervening washer 30, as shown by Fig. 1, adapted to be replaced, from time to time, to compensate for wear. Instead

of employing the single elongated sleeve 21, two spaced short sleeves may be used, as shown by Fig. 4. Each of these sleeves 31 are splined, by means of a key 32, to the shaft 20 and are journaled, as indicated by 70 33, within the end of the stationary sleeve 34 which may extend nearby to the side-wall of the casing and may have a bore 35 large enough, if desired, to clear the shaft 20. 75

The manner of mounting the clutch-member, according to which of the alternative constructions above-noted is used, will not be described. Where no rotary sleeve is employed, the clutch-member may be mounted directly on the shaft, as shown by Fig. 6; the stationary sleeve being proportioned to terminate a sufficient distance from said wall to provide the space for that purpose. In this example, the hub 36 of the clutch-member, to limit any undue end-play, is shouldered at 37 so as to bear against the collar 38 and it is extended at 39 into the side-wall so as to form, with the packing 26, an oil-tight arrangement. This hub 36 has a 80 85 sliding fit with the shaft 20; being also splined thereto by means of the key 40 so as to turn as a unit with the shaft. 90

In the example depicted by Fig. 1, the clutch-member, as before, occupies a position between the wall and the extremity of the stationary sleeve but, instead of resting directly on the shaft 20, it is carried by the periphery of the end-portion 41 of the rotary sleeve 21 and it terminates at 42 closely adjacent the washer 30 to limit its end-play to a permissible extent. 95

In the example of Fig. 4, the clutch-member 15 is rotatably mounted directly on the stationary sleeve 34 which is extended for that purpose nearly to the wall of the casing; a sufficient gap being provided to accommodate an annular flange 43 which integrally projects from the rotary sleeve 31 that, in this instance, is resorted to for the purpose of establishing a propelling relation between the shaft 20 and said clutch member. To that end, the hub 44 of the latter is provided with laterally projecting teeth 45 adapted to engage within recesses 46 cut 100 105 in the flange 43. This arrangement is notable, in that the gear and the clutch-member are both rotatably mounted on the same integral member (the fixed sleeve) and consequently easily admit of being co-axially related with great precision; thereby ensuring extreme smoothness in the action of the clutch and reducing to a minimum any untoward effect of such slight amounts of eccentricity as must needs exist between any 110 115 relatively rotatable elements however accurately assembled. 120

As has been stated, while this invention may embody various species of clutches, it admirably admits of the use of disk-clutches, 130

as for example, of the construction shown. Here, the clutch comprises an annular shoe 47 arranged adjacent the annular flange 14 of the gear. This shoe 47 is urged against 5 said flange by means of several symmetrically arranged levers 48 arranged in slots 49 cut in the periphery of the portion 18 and positioned by means of pivot-pins 50 secured to the levers and projecting from the sides 10 thereof; the projecting ends of the pivot-pins being seated in a recess 51 cut in the face of the flange 18. The inner end of the lever rests against the side of the shoe 47; preferably in a notch 52 so as to prohibit any 15 rotation of the shoe relative to the clutch-member 15.

The thrust resulting from the pressure of the shoe is, on the other side of the flange 14, resisted by an annular member which, for 20 convenience of assembly, may be made, as shown by Fig. 3, of two half-rings 53 and 54 hinged together by the pin 55 to form a complete circle. These half-rings have flanges 57 that are interiorly screw-threaded, as indicated by 58, so as to be adjustably affixed to the flange 18 of the clutch-member 15. A screw 56 serves to bind the parts securely in place, as will be understood.

It will be noted that the clutch-parts are 30 capable of a slight float or movement so a unit in an axial direction and in that a degree of self-adjustment in conformity with the position of the flange 14, is thereby provided; thus avoiding the "drag" sometimes 35 exhibited by faulty clutch designs.

To operate the clutches, a hand-lever 60 (Fig. 2) is affixed to a stub-shaft 61 journaled in a boss 62 provided by the frame or casing. To the inner end of such shaft 61, is affixed a lever 63 having a shoe 64 pivoted to its end and seated in a recess 68 provided by an enlargement 61 on the shift-rod 65. The latter is shown supported at its ends in the end-walls of the frame and it carries a member 67 having a slot 69 engaging a flange 70 projected from a conical lever-actuator 71 which, when moved laterally, may engage rolls 72 on the ends of the levers and operate the clutches as will be perceived.

The simplicity and compactness of the above-revealed organization is, especially noteworthy and it will be seen that it overcomes certain troublesome features of previous designs and is rugged and not likely 55 to become disarranged in use and may be assembled readily and subsequently adjusted as occasion demands to maintain accuracy and smoothness of action.

Without further analysis, the foregoing 60 will so fully reveal the gist of this invention that others can, by applying current knowledge, readily adapt it for various utilizations without omitting certain features that, from the standpoint of the prior art, fairly 65 constitute essential characteristics of the

generic or specific aspects of this invention, and therefore such adaptations should be and are intended to be comprehended within the meaning and range of equivalency of the following claims.

Having thus revealed this invention, I claim as new and desire to secure the following combinations and elements, or equivalents thereof, by Letters Patent of the United States:—

1. A motion-reverser combining a frame; a stationary sleeve rigidly supported thereby; a shaft translatable extending through said sleeve; a bevel-gear facing said sleeve; two oppositely-arranged bevel-gears meshing with said first gear and each journaled to rotate on the respective ends of said sleeve and out of contact with said shaft; two clutches operatively connected to said shaft and each arranged adjacent the outer ends 80 of said gears, respectively; and means for alternately engaging either clutch with its associated gear.

2. A motion-reverser combining a shaft; two oppositely-disposed gears spaced apart 90 in concentric relation with said shaft; non-rotatable means providing stationary journals for supporting said gears out of contact with said shaft; a frame rigidly connected with said stationary means; a clutch 95 located on said shaft adjacent each gear; and means independent of said shaft for establishing a driving relation between either of said gears and its associated clutch.

3. A motion-reverser combining a frame; 100 an elongated cylindrical member rotatably but non-translatable supported by said frame; two oppositely-disposed gears spaced apart in concentric relation with said rotary non-translatable member; means rigidly supported by said frame providing stationary journals for rotatably supporting said gears out of contact with said rotary member; two clutches mounted directly on 105 said rotary non-translatable member adjacent the outer end of each gear, respectively; and means shiftable relative to said member for establishing a driving relation between either of said gears and its associated clutch.

4. A motion-reverser combining a frame; a stationary sleeve rigidly supported thereby; a shaft translatable extending through said sleeve; a bevel-gear facing said sleeve; two oppositely arranged bevel-gears meshing with said first gear and each journaled to rotate on the respective ends of said sleeve and out of contact with said shaft; two clutches of the disk type operatively connected to said shaft and each arranged adjacent the outer ends of said gears, respectively; and means for alternately engaging either clutch with its associated gear.

5. A motion-reverser combining a frame; 125 a stationary sleeve rigidly supported there-

- by; a shaft translatable extending through said sleeve; a bevel-gear facing said sleeve; two oppositely arranged bevel-gears meshing with said first gear and each journaled to circumscribe the respective ends of said sleeve and out of contact with said shaft; two clutches mounted to circumscribe a portion of said sleeve and connected to said shaft and each arranged adjacent the outer ends of said gears, respectively; and means independent of said shaft for alternately engaging either clutch with its associated gear. 65
6. A motion-reverser combining a shaft; two oppositely-disposed gears spaced apart in concentric relation with said shaft; non-rotatable means providing stationary journals for supporting said gears out of contact with said shaft; a frame rigidly connected with said stationary means; a clutch located to circumscribe said non-rotatable means adjacent each gear; and means independent of said shaft for establishing a driving relation between either of said gears and its associated clutch. 70
7. A motion-reverser combining a frame; a stationary sleeve rigidly supported thereby; an elongated rotary member of tubular form extending through said sleeve; a bevel-gear facing said sleeve; two oppositely-arranged bevel-gears meshing with said first gear and each journaled to rotate on the respective ends of said sleeve and out of contact with said shaft; two clutches operatively connected to said tubular rotary member and each arranged adjacent the outer ends of said gears, respectively; and means for alternately engaging either clutch with its associated gear. 75
8. A motion-reverser combining a non-shiftable rotary sleeve; two oppositely-disposed gears spaced apart in concentric relation with said sleeve; non-rotatable means providing stationary journals for supporting said gears out of contact with said rotary sleeve, a frame rigidly connected with said stationary means; a clutch located on said non-shiftable rotary sleeve adjacent each gear; and means for establishing a driving relation between either of said gears and its associated clutch. 80
9. A motion-reverser combining a frame; an elongated cylindrical member rotatably supported by said frame; two oppositely-disposed gears spaced apart in concentric relation with said rotary member; means rigidly supported by said frame providing stationary journals for rotatably supporting said gears out of contact with said rotary member; two clutches having parts thereof mounted directly on said rotary member adjacent the outer end of each gear, respectively; means for establishing a driving relation between either of said gears and its associated clutch; and an independently 85
- shiftable shaft extending through said member and translatable splined thereto. 90
10. A motion-reverser combining a frame; a stationary sleeve rigidly supported thereby; a rotary sleeve within said stationary sleeve; a shaft translatable extending through said rotary sleeve; a bevel-gear facing said stationary sleeve; two oppositely arranged bevel-gears meshing with said first gear and each journaled to rotate on the respective ends of said stationary sleeve and out of contact with said shaft; two clutches carried by said rotary sleeve and thereby operatively connected to said shaft and each arranged adjacent the outer ends of said gears, respectively; and means for alternately engaging either clutch with its associated gear. 95
11. A motion-reverser combining a frame; a stationary sleeve rigidly supported thereby; a shaft translatable extending through said sleeve; a bevel-gear facing said sleeve; two oppositely arranged bevel-gears meshing with said first gear and each journaled to rotate on the respective ends of said sleeve and out of contact with said shaft; two clutch-members in splined relation with said shaft adjacent the outer ends of said gears, respectively; and adapted to move slightly in an axial direction; and means for alternately connecting either clutch-member with its associated gear. 100
12. A motion-reverser combining two oppositely-disposed gears spaced apart in coaxial relation; non-rotatable means providing stationary tubular journals for supporting said gears; a shaft translatable journaled within said tubular journals; a frame rigidly connected with said stationary means; a clutch-member circumscribing said shaft adjacent each gear; and means embodying a laterally-movable friction annulus for establishing a driving relation between either of said gears and its associated clutch-member, said annulus being shiftable independently of said shaft. 105
13. A clutch-mechanism combining a stationary tubular sleeve; a rotary sleeve interiorly journaled within said stationary sleeve near the end thereof; a shaft splined within said rotary sleeve; a gear journaled on said stationary sleeve near its end; a clutch-member also journaled to circumscribe said stationary sleeve between its end and said gear, said clutch-member being connected to rotate as a unit with said rotary sleeve; and means for causing said gear and clutch-member to rotate as a unit. 110
14. A motion-reverser combining a stationary hollow member providing journals at its ends; an intermediate bevel-gear arranged so closely to said member that its teeth barely escape contact therewith; a pair of bevel gears arranged on said journals in 115
- 120
- 125

- mesh with the opposite sides of said intermediate gear, the teeth of each of said bevel-gears being extended substantially to its bore; a shaft translatable extending through the bore of said hollow member; and means comprising a part located beyond the end of said member for transmitting motion at will between said shaft and the bevel-gear journaled on said member.
10. 15. A motion-reverser combining a casing; a translatable rotary shaft extending therethrough; a stationary sleeve around said shaft and terminating short of the end-walls of said casing; two spaced conversely-arranged bevel-gears journaled on said sleeve; means comprising clutch-elements extending from said shaft around the ends of said sleeve to said gears; spools for operating the clutch elements; and a shift-rod within said casing for operating said spools.
15. 16. A mechanism of the nature disclosed combining a fixed tube; a bevel-gear facing said fixed tube; an intermeshing bevel-gear journaled on said fixed tube; a thrust-bear-
- ing adjustable on said fixed tube to limit the retreat of said second gear from said first; a clutch unit arranged coaxially with said tube and adapted to shift slightly in an axial direction to conform to the position of said second gear; and means for frictionally engaging said unit with said gear.
20. 17. A frame having an apertured side-wall; a tubular-member having an end-portion projecting into said aperture; packing therebetween; a fixed sleeve terminating short of said side-wall; a shaft extending through said fixed sleeve and said tubular-member and splined to the latter; a gear journaled on said fixed sleeve; and means for causing said gear and member to rotate as a unit.
25. 30. 35. 40. In witness whereof, I hereunto subscribe my name, as attested by the two subscribing witnesses.

DAVID C. KLAUSMEYER.
